G. O'Brien

UNITED STATES PATENT OFFICE

2,534,745

BOMB SHACKLE

George W. Wardwell, Jr., Trumbull, Conn., assignor, by mesne assignments, to the United States of America as represented by the Secretary of the Navy

Application September 2, 1949, Serial No. 113,847

4 Claims. (Cl. 89—1.5)

1

This invention relates to release mechanisms and more particularly to a new and improved bomb shackle for use on aircraft.

In the manufacture of bomb shackles it is important to provide a structure which will be light in weight, will securely support a heavy bomb in spite of rough flying conditions and relatively large inertia forces, and yet will positively and immediately release the bomb upon actuation of the release mechanism. It is also of importance that the shackle permit rapid loading in the field without requiring special tools or machinery.

It is an object of the present invention to provide a bomb release device which has great simplicity and which will quickly release a bomb irrespective of the position of the aircraft.

Another object of the invention is to provide a shackle which can be quickly recocked when another bomb is to be loaded.

A further object is the provision of a bomb shackle of simple construction which has a single operating means which may be actuated both to release a bomb and to recock the shackle when another bomb is to be engaged.

Still another object of the invention is to provide a safe, positive releasable locking means for a bomb shackle that will effectively retain it in a bomb holding position yet requires but slight exertion to trip the mechanism and release the bomb.

Other objects and their attendant advantages will become apparent from the following description and attached drawings wherein:

Fig. 1 is a longitudinal section through one embodiment of the present invention with the parts in unlocked or released position; and

Fig. 2 is a change position view similar to Fig. 1 but showing the parts in locked position.

In the embodiment illustrated in the drawings there is provided a frame 7 of sheet material and comprising a pair of spaced elongated side plates 8 and 9 which may be interconnected at their tops by a horizontal web 10, at one end by a vertical web 11, and at their lower edges by a bottom web 12 essentially as shown.

At the ends of the frame are located hangers yoked at their lower ends 13 and 14 to embrace the exterior of the frame and be welded or otherwise secured thereto. The upper part of each of the hangers may be transversely bifurcated at 15 so as to receive the usual bomb rack mounting members (not shown) affixed to the plane. The notches 15 are bridged by short horizontal pins 16 mounted between spaced vertical webs 17

2

located within the hollow portion of the hangers as shown.

Between the plates 8 and 9 are located a pair of bomb supporting hooks 18 and 19 which are pivotally disposed at opposite ends of the shackle on hook pivot pins 20 and 21 secured through the plates and the lower ends 13 and 14 of the hangers. The hooks in the locked position of Fig. 2 sufficiently close the entrance of openings 13' and 14' to support bomb eyes 22 or other suitable members which are attached to the bomb.

In a suitable slot in an extended rear portion of the hook 18 there is pivoted on a link pin 23 one end of an elongated operating link 24, the other end of which link is connected by means of a link pin 25 to a toggle plate assembly 26 pivoted centrally in the frame on a link pin 27. The toggle plate assembly 26 may comprise a pair of matching plates spaced to receive the narrowed end of the link 24 as shown. In a suitable slot on the upper end of the hook 19 and at a distance from its fixed pivot 21 equal to the distance between the hook pivot 20 and link pin 23 of the hook 18 there is pivoted on a link pin 28 the end of a second operating link arm 29, the other end of which is pivoted by means of link pin 30 to the toggle plate assembly 26, link pin 32 being located opposite link pin 25.

Link pins 23 and 28 are so disposed relative to the hook pivots 20 and 21 respectively that when the link arms are moved to open or close the hooks 18 and 19, the link pin 23 will describe an arc below the hook pivot 20 and the link pin 28 will describe an arc above the hook pivot 21. Hence, it will be apparent that turning movement of the toggle plate 26 will simultaneously move the link arms 24 and 29 in opposite directions and, furthermore, movement of the toggle plate in a clockwise direction in Fig. 1 has the effect of moving the hooks to the closed or bomb supporting position of Fig. 2.

Releasable means for closing and locking the hooks in bomb supporting position is provided and this means will now be described. Freely mounted on pin 27 between the plates of toggle assembly 26 is a trip lever 31 which when moved in a clockwise direction in Fig. 1, engages toggle plate spacer pins 32 and 33 to cause the spaced toggle plates to rotate and the links and their hooks to move the bomb supporting position of Fig. 2. To retain the toggle plates in rotated position a shoulder 34 on the toggle plate is engaged by a spring pressed toggle plate detent arm 35 which carries a roller 36. This arm is pivoted

on a detent pin 37 and is biased upwardly by means of a detent spring 38.

It should be noted here that the weight of the bombs hanging on the closed hooks will tend to compress the links however movement of the links is prevented by the substantially straight line positioning of the links with respect to the center pivot 27 of the toggle plate. It will be apparent that in the secured position there is some but not much rotative torque applied against the toggle plate detent 36, and most of this is preferably furnished by the tension of a toggle spring 39.

Lever 31 is provided with a toe 40 extending slightly below the lower surface of the toggle plates 26 and having an inclined cam surface 41 such that when the lever is moved in a counter-clockwise direction the cam surface 41 acts on the detent roller 35 to force the detent arm 36 downwardly to move the detent roller clear of the shoulder 34.

When the detent arm 36 has been thus disengaged the torque exerted on the toggle plate 26 by the toggle spring 39, in combination with the force exerted on the toggle by the weight of the bomb hanging on the hooks 18 and 19, acts to move the link arms 24 and 29 toward each other and cause the hooks to open so as to drop the bomb. To cushion and limit the movement of the link arms when the bomb is released suitable limit pins 43 encased in a casing of rubber or other compressible material may be mounted between the plates 7 and 8 so as to be engaged by the sides of link arms 24 and 29 as shown in Fig. 1.

It will be apparent that with the above-described arrangement a light pressure will suffice to operate the trip lever and free the toggle from its detent.

It should be understood, of course, that the foregoing disclosure relates to only a preferred embodiment of the invention and that numerous modifications or alterations may be made therein without departing from the spirit and scope of the appended claims.

What is claimed is:

1. A bomb shackle comprising a frame, a pair of bomb supporting hooks pivotally supported on the frame for movement between opened and closed positions, a link arm connected to one of the hooks below its pivot point, a second link arm connected to the other hook above its pivot point, toggle means interconnecting both link arms for moving them in unison in opposite directions to simultaneously move the hooks to opened or closed position, an operating lever mounted for oscillatory movement adjacent the toggle, and stops positioned in the path of oscil-

lation to engage the toggle at the end of each oscillation and operate the toggle.

2. A bomb shackle comprising a frame, a pair of bomb supporting hooks pivotally supported on the frame for movement between opened and closed positions, a link arm connected to one of the hooks, a second link arm connected to the other hook, toggle means interconnecting both link arms for moving them in unison to simultaneously move the hooks to opened or closed position, an operating lever mounted for oscillatory movement adjacent the toggle, stops engageable at each limit of oscillation to engage the toggle to move it, detent means to retain the toggle in closed position, and an extension on the operating lever for engagement with the detent to disengage the detent before the toggle is tripped.

3. A bomb shackle comprising a frame, a pair of bomb supporting hooks pivotally supported on the frame for movement between opened and closed positions, link arms connected to the hooks for moving them to opened and closed positions, camming means interconnecting the link arms for moving them in unison to simultaneously move the hooks to opened or closed position, an operating lever mounted for oscillatory movement adjacent the camming surface, and detent means to prevent opening of the hooks, said detent being releasable by initial movement of the lever.

4. A bomb shackle comprising a frame, a pair of hooks pivoted in the frame at opposite ends thereof, a link arm connected to each of the hooks one link arm being connected below the pivot point of one hook and the other link arm being connected above the pivot point of the other hook, toggle means supported in the frame and interconnecting the free ends of each of said link arms, an operating lever adjacent the toggle and linked thereto to move the link arms simultaneously in opposite directions, a detent engageable with said toggle, means for resiliently biasing the toggle toward a bomb release position, and a toe on the operating lever engageable with the detent when the operating lever is moved in a bomb releasing direction whereby the detent is freed before the toggle is released.
